UNITED STATES PATENT OFFICE.

GEORGE N. HALLER, OF WASHINGTON, DISTRICT OF COLUMBIA, ASSIGNOR OF ONE-HALF TO IRVING SEIGEL, OF WASHINGTON, DISTRICT OF COLUMBIA.

COMBINED ACCELERATOR AND FOOT REST.

Application filed March 2, 1927. Serial No. 172,099.

My invention relates to a combined accelerator and foot rest for automobiles.

As is well known, when driving an automobile, particularly upon a long trip, the operator's foot which holds the accelerator lever depressed, becomes tired, causing considerable inconvenience. Further, as there is no rigid support for the foot, retaining the accelerator element depressed, the jars or shocks transmitted to the traveling automobile, are in turn transmitted to the foot and to the accelerator. This will cause the engine to run at uneven speeds.

In accordance with my invention, I provide a combined accelerator and foot rest, embodying a foot engaging member which is connected with the throttle valve of the carburetor, for effecting its opening movement, when the foot engaging member is depressed. Means are provided to hold or lock the foot engaging member against downward movement, when it is desired that the same serve as a rigid foot support or rest. The construction of the means is such that the foot engaging member will be automatically released, so that it may be freely depressed by the foot or rigidly supported against downward movement in any selected depressed position. When the foot engaging member is rigidly supported in a selected depressed position, it will not only afford a rigid support or rest for the foot but will hold the throttle valve of the carburetor in the selected open position, without subjecting the same to vibrations or movements, which occur with the use of the ordinary accelerator, particularly when an automobile is driven at a high speed.

The device is of simple construction and readily applied to the standard types of automobiles without materially altering the construction of the same.

In the accompanying drawings, forming a part of this specification, and in which like numerals are employed to designate like parts throughout the same,

Figure 1 is a side elevation of the device embodying my invention, showing the same applied to an automobile,

Figure 2 is a side elevation of the com-

bined accelerator and foot rest embodying my invention,

Figure 3 is a plan view of the same,

Figure 4 is a central longitudinal sectional view through the device,

Figure 5 is a transverse section taken on line 5-5 of Figure 4,

Figure 6 is a similar view taken on line 6-6 of Figure 4,

Figure 7 is a similar view taken on line 7-7 of Figure 4,

Figure 8 is a detailed fragmentary side elevation of the lever for actuating the throttle valve of the carburetor, and associated elements, and,

Figure 9 is a transverse section taken on line 9-9 of Figure 4.

In the drawings, wherein for the purpose of illustration, is shown a preferred embodiment of my invention, the numeral 10 designates an internal combustion engine of an automobile having the usual carburetor 11, embodying a throttle valve (not shown) which is opened by a lever or crank 12 when this lever or crank is shifted forwardly. As is well known, a spring is employed to normally retain the throttle valve of the carburetor closed, and such throttle valve is opened in opposition to this spring, by swinging the lever 12 forwardly. The numeral 13 designates the inclined floor board or bottom of an automobile body. It might be stated that this description of the automobile will be sufficient, as the invention is not restricted to its application upon any particular type of automobile and the showing is simply given to illustrate the application of the device to the automobile.

My combined accelerator and foot rest embodies an annular support or body portion 14, equipped with a radial annular flange 15, which is rigidly attached to the bottom 13 by any suitable means, such as screws passing through the openings 16.

The annular body portion 14 is equipped with a pair of longitudinal openings 17, slidably receiving guide rods 18 and 19, which are rigidly attached, by means of screws 20 or the like, to a guide sleeve or collar 21. The rod 19 extends forwardly beyond this

guide sleeve or collar 21, for a purpose to be described.

The guide rods 18 and 19 extend rearwardly beyond the body portion 14 and are rigidly connected with a foot engaging member 22, by means of screws 23 or the like. This foot engaging member is shown in the form of a circular disk, but the invention is in no sense restricted to this precise construction.

The foot engaging member or disk 22 is provided preferably centrally thereof with a tapered transverse opening 24, disposed between the guide rods 18 and 19, for the reception of a valve actuating element or button 25, having its outer end or nose 26 projecting rearwardly beyond the rear face of the foot engaging member 22. Since this element or button is arranged centrally of the member 22, the outer portion of the member 22 may be engaged by the foot and function as an accelerator, without necessitating the element or button 25 being depressed, or the foot may be shifted upon the member 22 to cover and depress the button whereby the member 22 will then serve as a foot rest. The numeral 27 designates a cylinder, the rear end of which has screw-threaded engagement within a tubular coupling 28, having screw-threaded engagement within the annular body portion 14, as shown. I preferably provide packing 29 between the rear end of the cylinder 27 and an annular wall or partition 30, formed in the coupling 28, for effecting a fluid tight joint. Mounted to reciprocate within the cylinder 27 is a tubular plunger 31, having a central port or bore 32, leading into recesses 33 and 34, upon opposite ends of the plunger. This plunger 31 is equipped with an annular recess 35, receiving packing 36. The recess 34 is screw-threaded for receiving the screw-threaded end of a tubular plunger rod 37, which is accordingly rigidly attached to the plunger 31. This tubular plunger rod has a lateral port 38, discharging into the open recess 39. The plunger 31 is provided adjacent to the upper end of the port or bore 32 with a conical valve seat 40. A cylindrical valve element 41 is slideable within the tubular plunger rod 37, and its lower end when moved forwardly is adapted to cover the port 38 and this valve element has a conical portion 42, to engage the conical valve seat 40, and a reduced cylindrical extension 43, to enter and close the bore 32. The cylinder 27 is adapted to be suitably filled with a fluid, preferably a mixture of castor oil and alcohol, or any other suitable mixture which will not readily freeze. This fluid is held within the cylinder 27 beneath the plunger 31 and is adapted to pass through the bore 32 to the top of the cylinder 27, when the plunger is moved downwardly in the cylinder 27, provided

the upper end of the bore is uncovered. It might be stated at this point that the discharge of the fluid through the upper end of the bore 32 is prevented at three points, namely, by the cylindrical valve element 41 covering port 38, by the reduced extension 43 entering the bore 32, and by the conical portion 42 engaging upon the conical valve seat 40. These three closures are adapted to effect a positive seal.

At its rear or upper end, the tubular plunger rod 37 is provided with a cylindrical screw-threaded head 44, receiving thereon a cylindrical housing or casing 45, provided in its top with a conical central opening 46, to receive the lower end of the conical button 25. The valve element 41 extends through the head 44 and is attached to the button 25 as shown at 47. The head 44 is provided with a recess for receiving packing 48, surrounding the valve element 41 and held in place by a gland 49. A conical compressible coil spring 50, surrounds the valve element 41 above the gland 49 and also engages the button 25, for holding the same upon the wall of the opening 46. Surrounding the tubular plunger rod 37 is a conical compressible coil spring 51, engaging the head 44, and a gland 52, having screw-threaded engagement within the tubular coupling 28, and holding packing 52', in place, which packing surrounds the tubular plunger rod 37, as shown. The spring 51 serves to hold the plunger rod 37 and the elements carried thereby, in the upper or rear position, with the housing 45 in contact with the wall of a recess 53, formed in the lower or forward face of the member 22. It is thus seen that when the member 22 is depressed, the housing 45 engaging behind this member, will cause the plunger rod 37, plunger and associated elements to travel as a unit with the member 22.

The lower or forward end of the cylinder 27 is covered by a head or cap 54, having screw-threaded engagement therewith and packing 54' is arranged between these parts, as shown. This cap is preferably provided with a trunnion or boss 55, upon which is mounted an upstanding arm or bracket 56, clamped thereto by means of a nut 57 or the like.

The numeral 58 designates a lever provided at its upper end with a cylindrical head 59, pivoted upon a bolt 60, carried by the arm or bracket 56. This lever is provided in its lower portion with a longitudinal slot 61, receiving the forward flattened end 62 of the guide rod 19. A transverse pin 63 is attached to this flattened end 62 and operates within longitudinal slots 64. Pivotedly connected, at 65, with the lower end of the arm 58, is a rod 66, extending forwardly and slidably projecting through an opening 67, formed in the upper end of

the lever 12. In advance of the lever 12 the rod 66 carries a collar or stop 68, clamped thereto. It is thus seen that when the rod 66 is moved forwardly in the direction of its arrow that it will shift the lever 12 forwardly to open the throttle valve, but the connection is such that the lever 12 may be shifted forwardly by the usual gas lever on the steering wheel independently of the movement of the rod 66.

The operation of the device is as follows: When the foot is removed from the foot engaging member 22 such member will assume the raised or rear position, and the plunger 31 and associated element will assume the raised or rear position, as indicated in Figure 4. With the parts in this position, the engine may be operated by means of the usual gas lever at the steering wheel. When driving the automobile, the throttle valve of the carburetor may be operated by my device, and to accomplish this, the member 22 is depressed by the foot, without depressing the button 25. As the rear or upper end of the bore 32 is now opened or uncovered, the fluid within the forward or lower end of the cylinder 27 may pass to the upper end thereof and hence the plunger 31 is free to slide in either direction within the cylinder 27. When the member 22 has been depressed to the selected position, it may be locked in this position against further depressing movement, so that it will serve as a rigid foot rest. To accomplish this, the foot is shifted upon the member 22 until it covers the button 25 and this action of the foot will depress the button, with relation to the member 22. This will cause the valve element 41 to be depressed with relation to the tubular plunger rod 37 and the port 38 will be covered, conical part 42 will engage conical valve seat 40, and the reduced extension 43 will enter the bore 32. The upper end of the bore is, therefore, effectively closed and the fluid can not pass from the lower end of the cylinder to the upper end of the cylinder, and hence the plunger 31 will be locked against further depression. The foot remaining upon the member 22 and button 25, will be rigidly supported, the device then functioning as a foot rest. Further, the device will hold the rod 19 against perceptible longitudinal movements, and hence the throttle valve of the carburetor will be held set in the adjusted opened position, and the speed of the engine will be retained uniform. When the foot is shifted from the button 25, the spring 50 will immediately shift the valve element 41 to the open position, and the fluid will then be free to circulate through the bore 32, and hence the plunger 31 and member 22 will be free to partake of reciprocatory movements. Hence the pressure may be moved from the member 22 and it

will automatically return to the raised position, and rod 66 will return to the rearmost position, whereby the spring of the carburetor will automatically return the throttle valve to the wholly or partly closed position. 70

It is to be understood that the form of my invention, herewith shown and described is to be taken as a preferred example of the same, and that various changes in the shape, size and arrangement of parts may be resorted to without departing from the spirit of my invention or the scope of the subjoined claims. 75

Having thus described my invention, I claim:—

1. A combined foot rest and accelerator for a motor driven vehicle comprising, a support, a foot engaging member connected with the support and adapted to be depressed by the foot, means for connecting the foot engaging member with a movable element of the carburetor, hydraulic means adapted to positively hold the foot engaging member against depressing movement, and means for actuating the hydraulic means so that the foot engaging member may be released for depressing movement, said actuating means embodying a foot engaging element arranged near the foot engaging member. 90

2. A combined foot rest and accelerator for a motor driven vehicle comprising, a support, a foot engaging member connected with the support and adapted to be depressed by the foot, means for connecting the foot engaging member with a movable element of a carburetor, hydraulic means adapted to positively hold the foot engaging member against depressing movement, and means for actuating the hydraulic means to release the foot engaging member for depressing movement, said actuating means embodying a foot engaging element which is movable with and with relation to the foot engaging member. 100

3. A combined foot rest and accelerator for a motor driven vehicle comprising, a support, a foot engaging member connected with the support and adapted to be depressed by the foot, means for connecting the foot engaging member with a movable part of a carburetor, hydraulic means for controlling the depression movement of the foot engaging member, and means for controlling the escape of fluid from a part of the hydraulic means including an element carried by and movable with relation to the foot engaging member. 115

4. A combined foot rest and accelerator for a motor driven vehicle comprising, a foot engaging member, means for connecting the member with a movable element of a carburetor, a cylinder, a tubular plunger within the cylinder, a rod connecting with the plunger and adapted to be moved by 125

130

- the foot engaging member, a foot engaging element arranged near the foot engaging member, and means to cover the opening of the tubular plunger and connected with the 5 foot engaging element.
5. A combined foot rest and accelerator for a motor driven vehicle comprising, a foot engaging member having an opening therein, a foot engaging element mounted within the 10 opening and projecting rearwardly beyond the member, means for connecting the member with a movable element of a carburetor, a cylinder for holding a fluid, a plunger within the cylinder having a port for the 15 passage of the fluid, means for controlling the passage of the fluid through said port and connected with the foot engaging element, and connecting means between the plunger and the foot engaging member.
- 20 6. A combined foot rest and accelerator for a motor driven vehicle comprising, a foot engaging member having an opening therein, a foot engaging element within the opening and projecting beyond the rear 25 face of said member, means for connecting said member with a movable element of a carburetor, a cylinder holding a fluid, a plunger within the cylinder having a port for the 30 passage of the fluid, a tubular rod connected with the plunger and engaging the foot engaging member, and a valve element operating within the tubular rod and controlling the passage of fluid through said 35 port and connected with the foot engaging element.
7. A combined foot rest and accelerator for a motor driven vehicle comprising, a foot engaging member, a foot engaging element carried by said member and movable 40 with it and with relation to the same, a cylinder, a plunger within the cylinder having a port, a tubular rod connected with the plunger and adapted to be shifted by the member, a valve element to cover the port 45 and connected with the foot engaging element, a spring to move the foot engaging element in one direction, and a spring to move the foot engaging member in one direction.
- 50 8. A combined foot rest and accelerator for a motor driven vehicle comprising, a shell for holding a fluid, a movable member within the shell and having its movement controlled by the passage of fluid within the 55 shell from one side of the member to its opposite side, means for controlling such passage of the fluid, a foot engaging member connected with the movable member so that the movement of the former is controlled by that of the latter, a foot engaging 60 element connected with the fluid control means, and means connecting the foot engaging member with a movable part of the carburetor.
9. A combined foot rest and accelerator 65 for a power driven vehicle comprising, a shell for holding a fluid, a movable member within the shell and adapted to move therein upon the escape of fluid from the shell upon one side of the movable member, a foot engaging member having its movement controlled by the movement of said movable member, means connecting the foot engaging member with a movable part of the carburetor, and means for controlling the escape 70 of the fluid from the shell upon the side of the movable member including a movable foot engaging element carried by and movable with relation to the foot engaging member. 75
10. A combined foot rest and accelerator 80 for a motor driven vehicle comprising, a shell for holding a fluid, a movable member engaging the fluid within the shell and having its movement controlled by the escape 85 of the fluid from the shell upon one side of the movable member, a foot engaging member having its movement controlled by the movement of the movable member, means connecting the foot engaging member with a movable part of the carburetor, a valve element for controlling the escape of the fluid from the shell upon one side of the movable member, automatic means to shift the valve element to the open position, 90 and a foot engaging element connected with the valve element to move it to the closed position. 95
11. A combined foot rest and accelerator 100 for a motor driven vehicle comprising, a support, a foot engaging member connected with the support and adapted to be depressed by the foot, means for connecting the foot engaging member with a movable element of a carburetor, hydraulic means connected with the foot engaging member and having an opening for the passage of fluid, said hydraulic means being so constructed 105 that the foot engaging member may move when said passage is uncovered and said hydraulic means positively holding the foot engaging member against movement when the passage is covered, and normally open means to cover and uncover the passage, said means being adapted to be moved to the closed position by the foot to cover said passage. 110

In testimony whereof I affix my signature.

GEORGE N. HALLER.
